COLLAPSIBLE TUBING WITH PROTECTIVE RIB

William E. Rejeski, Farmington, Conn., assignor to The Wiremold Company, West Hartford, Conn., a corporation of Connecticut

Application June 9, 1955, Serial No. 514,285

14 Claims. (Cl. 138—60)

This invention relates to improvements in collapsible tubing formed of a convoluted metal strip, the adjacent convolutions of which are connected by fabric or other flexible material in the form of a strip which may be comprised of one or more laminations whose edges are frictionally held by the folded-over edges of the metal strip. More particularly, the invention relates to the provision of a scuff rib in such tubing.

Collapsible tubing made of two or more elements has heretofore been made including various structural improvements to improve the flow of air or gas and to protect the flexible strip from wear and scuffing, particularly where it is joined to the metal strip. While some of these prior structures have gone into use and been satisfactory under some conditions, there are conditions of use which require greater protection of the flexible strip and a smoother interior surface to improve the flow and also to avoid being caught on sharp objects. Also, the prior structures which aimed to satisfy the foregoing conditions were not well adapted to laminated flexible strips since laminations, when folded, tend undesirably to increase in bulk at the fold and make it difficult, if not impossible, to fabricate a satisfactory joint with a metal strip.

Therefore, one object of the invention is to provide an improved collapsible tubing construction in which a laminated flexible strip can be used to join adjacent convolutions of a metal strip whose edges frictionally hold the flexible strip.

Another object is to provide an improved collapsible tubing construction having a scuff rib on the metal strip outside the tubing to protect the tubing and in a position where it can be controlled.

Another object is to provide an improved collapsible tubing construction of the foregoing type in which the interior is smoother, providing for freer flow of gas than heretofore.

Other objects and advantages of the invention will appear as it is described in connection with the accompanying drawing.

In the drawing:

Fig. 1 is a fragmentary longitudinal section view of two convolutions of collapsible tubing embodying the invention.

Fig. 2 is a view similar to Fig. 1 but of another form of the invention.

Fig. 3 is a view similar to Fig. 1 but of a third form of the invention.

Fig. 4 is a view similar to Fig. 1 of a fourth form of the invention.

Referring to the drawing, the tubing comprises a helically wound spring wire 10 over and around which a strip of metal is folded on its longitudinal center line. Preferably, the interior surfaces of the portions 12 and 14 of the trailing and forward portions, respectively, of the strip, now lying on opposite sides of the wire 10, are bent into engagement inside the wire helix. Both por-

2

tions 12 and 14 are continued radially inward a short distance, and then bent oppositely parallel to the axis of the tubing, as at 16 and 18. The trailing and forward edges 24, 26 of the metal strip are reversely bent outwardly and folded down over the outer surfaces of the axially-directed portions 16, 18 respectively.

The flexible component of the tubing (as distinguished from the helical spring wire 10 and the metal strip both of which are resilient in different degrees, but not flexible or pliable like a piece of cloth or thin plastic sheeting) may comprise a flexible strip of cloth, fabric, synthetic plastic sheeting or other limp flexible material, i. e., lacking stiffness. The strip may have one, two or more layers or laminations. The laminations may be of the same or different materials to satisfy different conditions inside and outside the tubing. For example, but not by way of limitation, the inner lamination 30 may have to resist temperatures well above room temperature while the outer lamination 40 may have to withstand wear and rough handling. Also, a third lamination 50 such as of insulation is sometimes necessary between the inner and outer layers as shown in Fig. 4, in which like numerals represent like parts of Fig. 1. Hence, when referring to the flexible strip, it will be understood that a single or multiple laminated strip is contemplated, without specific limitation as to the number of layers.

Prior to folding down the metal strip edges 24, 26 all the way, the trailing edge 32, 42 of the flexible strip is turned under, and the turned-under edge is inserted under the forward edge 26 of one convolution of the metal strip; and the forward edge 31, 41 of the flexible strip is similarly turned under and is inserted under the trailing edge 24 of the adjacent convolution of the metal strip. Thereafter, the folded edges 24, 26 of the metal strip are bent down tightly on the inserted flexible strip edges 31, 32 to frictionally hold them and all laminations thereof with a firm and permanent grip.

By pressing the edges 24 and 26 toward the periphery, the metal strip where the latter surrounds the wire, or vice versa, the flexible strip can be pinched therebetween to provide additional holding of the elements.

The spring 10 expands the tubing when not stored or under compression for other reasons. Although this spring is desirable in some instances, such as in large diameter tubing, it may not be necessary in all cases and may be omitted, if desired. The metal strip, being formed in a helix, suffices in such cases to expand the tubing; or the tubing may be pulled to full length.

In the form of the invention of Fig. 2, the spring wire has been omitted but the metal strip is laterally bent circularly along its longitudinal central axis as in the previous form. Instead of being bent radially inward after touching, the trailing and forward portions 112, 114 are reversely bent a short distance and then bent parallel to the axis of the tubing, but in opposite directions as at 116, 118. Then, their longitudinal edges 124, 126 are bent reversely inwardly in position to grip between themselves and the portions 116, 118 respectively, the longitudinal edges 132, 142 and 131, 141 of the flexible strips to frictionally hold the same when the reversely bent edges are pressed toward the portions 116, 118.

In the form of the invention of Fig. 3, one half (shown only for example as the left half) of the metal strip—as viewed in cross section and on either sides of the radial median line of itself and of the tubing—is formed as in the form of Fig. 1, while the other (right half) is formed as in the form of Fig. 2. Alternatively, the right half could be as in Fig. 3 and the left half as in Fig. 1. In Fig. 3, similar reference numerals are used to those of Figs. 1 and 2 but with a prime (') added.

It will be clear that in each of the possible forms, a scuff rib is formed by the bending of the metal strip; and

that rib will protect the outside of the flexible strip of the tubing from abrasion, wear and tear. Also, in each form, the spring wire can be used as conditions indicate the need, or dispensed with when not necessary. Further, each form is adapted to permit the use of a plurality of plies, layers or laminations of the flexible strip without the joint of the flexible strip with the metal strip becoming too bulky.

In each of the forms, the protrusion of the metal can be controlled so that it need only project as far as may be necessary or desirable regardless of the number of laminations used in the flexible strip.

Many modifications within the scope of the invention will occur to those skilled in the art. Therefore, the invention is not limited to the specific configurations shown.

What is claimed is:

1. Collapsible tubing comprising a metal strip wound into a helical spiral, the edges of said strip being reversely bent, a flexible strip having an edge inserted between said reversely bent edge and the body of the strip and frictionally held thereby, the opposite edge of said flexible strip being inserted between the opposite edge and body portions of an adjacent convolution of said metal strip, the portion of said metal strip between its reversely bent edges being bent outwardly beyond the portions of the strip paralleling said reversely bent edges to form a protective rib exterior of the tubing and extending beyond the circumference of the tubing.

2. Collapsible tubing as claimed in claim 1 in which the flexible tubing is laminated, one lamination being capable of resisting temperatures above room temperature, another lamination being wear-resistant.

3. Collapsible tubing as claimed in claim 2 having an intermediate third lamination of insulating material.

4. Collapsible tubing as claimed in claim 1 in which the rib is tubular in cross section.

5. Collapsible tubing as claimed in claim 1 having a spring wire within the rib tending to expand the tubing.

6. Collapsible tubing as claimed in claim 1 in which the reverse bend of at least one edge of the metal strip is outward and a portion of the flexible strip lies upon the outside of said reversely bent edge.

7. Collapsible tubing as claimed in claim 6 in which the rib is tubular in cross section.

8. Collapsible tubing as claimed in claim 7 having a spring wire within the rib tending to expand the tubing.

9. Collapsible tubing as claimed in claim 7 in which the flexible tubing is laminated and in which said rib bears against said flexible tubing pressing it against the reversely bent edge of the metal strip.

10. Collapsible tubing as claimed in claim 1 in which the flexible tubing is laminated.

11. Collapsible tubing as claimed in claim 1 in which the rib is tubular in cross section, said rib bearing against said flexible tubing and pressing it against the reversely bent edge of the metal strip.

12. Collapsible tubing as claimed in claim 1 in which the reverse bend of at least one of the edges of the metal strip is inward.

13. Collapsible tubing as claimed in claim 12 in which the rib is tubular in cross section.

14. Collapsible tubing as claimed in claim 1 in which one edge of the metal strip is reversely bent outwardly and the other edge is reversely bent inwardly.
